PISTON

Ralph R. Teetor, Hagerstown, Ind., assignor to
The Perfect Circle Company, Hagerstown, Ind.,
a corporation of Indiana

Application July 31, 1934, Serial No. 737,800

6 Claims. (Cl. 309—13)

This invention relates to pistons for internal combustion engines and the like.

The principal object of my invention is to provide a piston so constructed that the desired clearances between the skirt and cylinder wall at right angles to the piston pin may be maintained throughout the operating range of the engine. I provide a piston of aluminum alloy or the like which is simple in structure and cheap to manufacture, while at the same time the piston is free from the objectionable defects present in the slotted skirt type of aluminum pistons now on the market.

The above and further objects of my invention will appear more fully from the following description, reference being had to the accompanying drawing in which:

Fig. 1 is a vertical sectional view through a piston embodying the preferred form of my invention;

Fig. 2 is a vertical sectional view through the piston, the section being at 90° to that of Fig. 1;

Fig. 3 is a cross sectional view through the piston, taken on line 3—3 of Fig. 1; and

Figs. 4 and 5 are plan and side views, respectively, of one of the cross struts.

The piston comprises a head 16 separated from the skirt 17 by the slot 18. The skirt is provided with piston pin bosses 19 and the head, upper portion of the skirt and the bosses are connected together by integral hangers or webs 20. The piston is formed of the usual aluminum alloy or the like.

Near the bottom of the skirt are two cross struts 22, formed of metal known as Invar, or steel or some other suitable metal having a lesser coefficient of expansion than the head and skirt. As illustrated in Figs. 4 and 5, one form of each strut may be L-shaped in cross section and have inclined end ears 23 provided with apertures 24. As best shown in Fig. 3, the end portions of the struts including the apertured ears 23 are embedded in thickened portions 25 of the skirt.

In casting the piston, above described, the cross struts are mounted in a mold and the piston is then cast so that the ends of the struts are embodied in the thickened portions of the piston skirt. In order to impart to the skirt the desired elliptical or out of round shape or form, I preferably take a piston after it has been cast, heat the head to approximately the temperature to which the head would be heated under normal operating conditions in an engine and then while the piston is in this heated condition size it by a tool brought into engagement with the skirt

of the piston while the piston is being rotated. The skirt after the sizing operation and while the piston head is hot is round or cylindrical. Upon cooling of the piston, the head shrinks more than the skirt and the hangers, being connected rigidly and directly to the top of the skirt, pull in the portions of the skirt in line with the pin bosses so that the skirt becomes elliptical with the major axis at right angles to the axis of the pin bosses. Using this cooled piston as a pattern, I form a cam to be used in a machine which will form or grind the skirts of other pistons in production to the desired elliptical form.

With the piston in the cylinder, when the engine is cold there is the correct clearance between the cylinder wall and the bearing surfaces of the piston skirt which are midway between the piston pin bosses. As the engine becomes heated in operation, the piston head is heated to a much higher temperature than the skirt with the result that the head tends to expand twice as much as the skirt or thereabout. The expansion of the head separates the hangers and thus increases the diameter of the top of the skirt in the plane of the axis of the pin bosses, the hangers being inflexible and connected directly to the upper portion of the skirt. In other words the expansion of the head tends to change the upper portion of the skirt from its elliptical form to one approaching a round form by increasing the diameter in the plane of the pin bosses so that it approaches the diameter at right angles thereto. This tends to decrease the latter diameter. At the same time, however, the aluminum of the skirt expands circumferentially due to the heat, so that while the expansion of the head may tend to reduce the major axis which is at right angles to the pin bosses, yet the inherent expansion of the skirt slightly more than compensates for this with the result that the desired clearance at the top of the skirt bearing faces is maintained. In other words, the distance between the bearing faces increases slightly as the diameter of the engine cylinder increases.

The struts 22 also perform the function of maintaining this desired clearance at the bottom of the bearing faces. After the piston is cast the aluminum cools so, of course, the struts are always in compression and they tend to maintain the diameter of the lower ends of the bearing faces about the same when the piston is cold as when it is hot. As the skirt becomes heated during operation of the engine, the aluminum expands circumferentially but the expansion necessarily takes place for the most part on the

minor axis of the skirt. This may tend to flatten out the bottom portions of the bearing faces between the ends of the struts but this tendency is slightly more than compensated for by the circumferential expansion of the skirt, so that as the diameter of the engine cylinder increases, the distance between the bottom portions of the bearing faces increases and the correct clearance between the cylinder wall and these portions of the bearing faces is maintained.

It will thus be seen that the diameter of the piston skirt from top to bottom is properly controlled during the operating range of the engine so that the desired clearance between the bearing faces and cylinder wall is maintained throughout their length, the diameter of the skirt in line with the pin bosses being permitted to change without impairing the efficiency of the engine and without danger of scoring and the like.

It is understood that my invention is not limited to the details of construction shown and that other forms may be used without departing from the scope of my invention.

I claim:

1. In a piston formed of metal having a high coefficient of expansion, a head, a continuous skirt of elliptical form in cross-section from one end thereof to the other, the upper edge of said skirt being separated from said head by a slot extending substantially throughout the circumference of the piston, rigid hangers connecting together said head and the upper end of said skirt, piston pin bosses on said skirt and on the minor axis of the ellipse of said skirt, and a pair of struts each formed of a material having a much lower coefficient of expansion than said skirt and disposed within said skirt below said pin bosses and parallel to the major axis of the ellipse of said skirt with their ends embedded in the wall of said skirt at points substantially spaced apart, said struts each being so shaped and constructed that they are inflexible and are of such length that they are held under constant compression by said skirt, the force of compression being sufficiently great that it will not be released by thermal expansion of said skirt during operation in an engine.

2. In a piston formed of metal having a high coefficient of expansion, a head, a continuous-walled skirt having an elliptical cross-sectional shape from one end to the other, opposed rigid hangers integral with and depending from said head and integrally connected to the upper end of said skirt on the minor axis of the ellipse of the latter, said head being separated from the upper end of said skirt at all points except at said hangers whereby said head is free to expand and contract in a uniform manner and without distortion, piston pin bosses formed on said piston adjacent the lower ends of said hangers with the remainder of the upper wall portion of said skirt free and unrestrained whereby expansion and contraction movements of said head acuate said hangers to expand and contract said skirt along the minor axis of its ellipse to produce, upon expansion, a substantially circular skirt and, upon contraction, an elliptical skirt, and a pair of struts each formed of a material having a much lower coefficient of expansion than said skirt and disposed within said skirt below said pin bosses and parallel to the major axis of the ellipse of said skirt with their ends integrally secured in the wall of said skirt at points substantially spaced apart whereby the skirt material between adjacent ends of said struts is free

to tend to flatten out during thermal expansion of the piston skirt, said struts each being so shaped and constructed that they are inflexible and are of such length that they are held under constant compression by said skirt, the force of compression being sufficiently great that it will not be released by the thermal expansion of said skirt during operation in an engine.

3. In a piston formed of metal having a high coefficient of expansion, the combination of a head and an elliptical continuous skirt with a slot therebetween extending substantially throughout the circumference of the piston, piston pin bosses integral with the skirt and on the minor axis of the latter, hangers integral with the head and upper portion of the skirt, the hangers being inflexible so that the expansion of the head upon being heated in an engine tends to change the upper portion of the skirt from its elliptical form to one approaching a round form, and struts having a lower coefficient of expansion than said skirt and arranged parallel to the major axis of the skirt in the lower portion of the skirt, the struts having their ends imbedded with the skirt and being of such length that they are held under constant compression by the skirt so that the circumferential expansion of the skirt upon becoming heated in an engine tends to change the lower portion of the skirt from its elliptical form to one approaching a round form, the length of the major axis remaining substantially constant.

4. In a piston formed of metal having a high coefficient of expansion, a head, a continuous-walled skirt having an elliptical cross-sectional shape with the bearing face portions on the major axis, piston pin bosses on the minor axis of the ellipse of the skirt, and two spaced-apart struts having a lower coefficient of expansion than said skirt and disposed within said skirt below and spaced from said pin bosses and substantially parallel to the major axis of said ellipse, the struts being inflexible and the bearing face portions between the ends of the struts being flexible, whereby said bearing face portions tend to flatten out during thermal expansion of the piston skirt and the length of the minor axis of the skirt increases.

5. In a piston formed of metal having a high coefficient of expansion, a continuous walled skirt having an elliptical cross-sectional shape from one end to the other with the bearing face portions on the major axis, opposed hangers rigidly connecting the upper end of the skirt to the head on the minor axis of the ellipse of the skirt, the skirt being separated from the head between the hangers, piston pin bosses within the skirt and on the minor axis of the ellipse of the skirt, and two spaced apart struts having a lower coefficient of expansion than said skirt and disposed within said skirt below and spaced from said pin bosses, and substantially parallel to the major axis of said ellipse, the struts being inflexible and the bearing face portions between the ends of the struts being flexible, whereby said bearing face portions tend to flatten out during thermal expansion of the piston skirt and the length of the minor axis of the skirt increases.

6. A piston comprising a head, rigid hangers depending from said head and carrying pin bosses apertured to receive a piston pin, and a skirt directly connected to said hangers and pin bosses, all formed of a metal having a high coefficient of expansion; said head and skirt being axially spaced from each other throughout their

entire circumference by a circumferentially extending air gap and being maintained in such relation by said rigid hangers, the entire exterior surface of said skirt being generally elliptical in contour with the minor axis thereof substantially parallel to the axis of said pin bosses and the continuity of said skirt being interrupted only

by the pin boss apertures, and a pair of rigid struts having a lower coefficient of expansion than that of the metal of said skirt disposed below and spaced from said pin bosses, the ends of said struts being embedded in the metal of said skirt. 5
